UNITED STATES PATENT OFFICE.

ERNEST H. PEABODY, OF NEW YORK, N. Y., ASSIGNOR TO THE BABCOCK & WILCOX COMPANY, OF BAYONNE, NEW JERSEY, A CORPORATION OF NEW JERSEY.

LIQUID-ATOMIZER.

1,150,960.

Specification of Letters Patent. Patented Aug. 24, 1915.

Original application filed January 5, 1910, Serial No. 536,457. Divided and this application filed January 2, 1913. Serial No. 739,720.

To all whom it may concern:

Be it known that I, ERNEST H. PEABODY, a citizen of the United States, residing at New York city, borough of Manhattan, in the county of New York and State of New York, have invented certain new and useful Improvements in Liquid-Atomizers, of which the following is a specification.

My invention relates to apparatus for spraying liquids and its object is to produce a spray in substantially a single plane without the use of compressed air or steam, the invention being particularly adapted to the spraying of liquid fuel for delivery to a boiler or other furnace, this application being a division of my application Serial No. 536,457, filed January 5, 1910.

In the accompanying drawings I have shown an atomizer or spraying device embodying one form of my invention.

In these drawings Figure 1 is a top view of the tip of the spraying device showing the spray issuing therefrom; Fig. 2 a top view of the nozzle with the tip removed; Fig. 3 a view in elevation of the tip showing the opening through which the spray issues; Fig. 4 a longitudinal section through the tip and nozzle and the connections to the supply pipe; Fig. 5 is a transverse section through the tip of Fig. 4; Fig. 6 a transverse section of a modified form of tip; Fig. 7 an inverted plan view of the tip showing the washer interposed between the tip and the nozzle; Figs. 8 and 9 top and sectional views, respectively, of the removable washer interposed between the tip and the nozzle; and Fig. 10 a horizontal section through the tip to indicate the effect of the centrifugal motion on the position of the spray.

Similar reference numerals indicate similar parts in the several views.

Referring to the drawings the numeral 1 designates a pipe to which the oil or other liquid to be sprayed is delivered from a suitable source, the pipe being properly supported and connected to suitable valves for controlling the delivery and pressure of the liquid to the tip. If the device is to be used for spraying liquid fuel and the construction of the furnace makes it necessary to deliver the oil through a vertical pipe, an elbow 2 is attached to pipe 1 and to this elbow is secured a nozzle 3. If a horizontal

pipe is used the nozzle may be secured directly to pipe 1. As shown in Figs. 4 and 5, 55 the nozzle is provided with substantially longitudinal passages 4 which deliver the oil to an annular channel 5 on the face of the nozzle. Resting on this face is a removable member 6, in the form of a washer, the central opening of which is of less diameter than the diameter of the channel 5. Extending tangentially to the wall of the opening 7 are passages 8 which open over the annular channel 5. 60

Secured to the nozzle is a tip 9, the washer 6 being clamped to the face of the nozzle by the tip, the latter having a chamber 10 the base of which is of substantially the same diameter as that of the central opening 7. 70 This chamber is preferably dome shaped so that its upper portion 11 is of less diameter than its lower portion, and in the wall of its upper portion an opening is provided through which the spray is discharged, such 75 opening being at a point other than one concentric with the axis of revolution of the liquid. In the form shown this opening is a slot 12 located in a plane at substantially a right angle to the axis of the tip, such 80 slot limiting the direction of the spray issuing from the tip and preventing its taking a form concentric about the axis of revolution of the liquid.

In Fig. 6 I have shown a slight modification of the tip in which the chamber 10 has a wider base than in the form shown in Figs. 4 and 5, and the side walls converging upwardly to the upper portion. 85

In practising my improved method by 90 the use of the described spraying device, which in the art is designated as an oil burner, the oil is delivered through the pipe 1 under pressure alone and without an accompaniment of compressed air, steam or 95 other spraying medium, and flowing through the passages 4, annular channel 5, and the tangential passages 8 is delivered with a rapid whirling motion into the chamber 10. The particles of oil upon reaching the slot 12 fly off tangentially, due to the action of 100 centrifugal force, the whirling of the liquid being so rapid as to cause some portions to fly in one direction and some in another, as indicated in Fig. 1, but all fly in substantially the same plane. A flat even spray is,

therefore, produced which, on being ignited, results in a flat flame as in atomizers using spraying media.

I am aware that spraying devices or oil burners have been used in which the spraying or atomizing of the liquid has been produced by centrifugal force resulting from a whirling motion imparted to the liquid. In these devices, however, the spray invariably issues from the tip in a conical form resulting, with oil fuel, in what is known as a "round flame." I am also aware that spraying devices have been used in which an atomizing or spraying medium, such as compressed air or steam, is employed to spray the liquid, and that such devices have produced a spray issuing from the tip in a single plane resulting in a flat or "fan-tail" form of spray, or what is known in the case of liquid fuel as a "flat flame." There are many instances where the flat flame is best adapted to the local conditions existing in a furnace giving a more uniform distribution of heat and better efficiency. There are, in fact, conditions in which a round flame burner cannot be used to give the desired results, and the superiority of the flat flame burners has resulted in the entire abandonment of the round flame burners in certain localities and in certain forms of furnaces. On the other hand, there are many instances in which oil is used as a fuel wherein the local conditions practically prohibit the use of atomizers in which an atomizing medium such as compressed air or steam is employed. This is true particularly in connection with marine work where steam cannot be used on account of the loss of fresh water and where compressed air necessarily situates the installation of heavy and objectionable compressing machinery and the use of large and unwieldy pipes throughout the boiler room. In installations of this character the class of oil burners in which oil is sprayed or atomized by means of a whirling

motion imparted to the oil by means of pressure has practically supplanted all other types, and it is to a device of this character that the present invention is directed. In the present device, however, the liquid is atomized or sprayed without the use of compressed air or steam, thereby obtaining the advantages of the flat flame without the objectionable features incident to the employment of compressed air or steam. 55

While I have described the passages 8 as tangential to the wall of the washer 6 and the wall of the chamber 10, I desire to include within said term any degree of eccentricity of said passages which will give to 60 the liquid a rapid whirling motion.

What I claim and desire to secure by Letters Patent of the United States is:—

1. In a spraying device for liquids, a nozzle having a chamber, and means for introducing a stream of liquid into said chamber tangentially thereof without the use of air or steam to produce a rotary movement of the liquid, said nozzle having a discharge slot through which the liquid is discharged 70 in a single plane; substantially as described.

2. In a spraying device for liquids, a nozzle having a chamber, and means for introducing a stream of liquid into said chamber tangentially thereof without the use of air 75 or steam to produce a rotary movement of the liquid, said nozzle having a discharge opening in a direction at substantially right angles to the axis of said chamber, whereby the liquid is discharged through said opening in a single plane substantially parallel to the plane of rotation in said chamber. 80

In testimony whereof I have hereunto signed my name in the presence of two subscribing witnesses.

ERNEST H. PEABODY,
